UNITED STATES PATENT OFFICE.

ANDREW W. HARPSTRITE, OF MOWEAQUA, ILLINOIS.

MOTOR-VEHICLE.

No. 927,463.

Specification of Letters Patent. Patented July 6, 1909.

Original application filed October 17, 1906, Serial No. 339,368. Divided and this application filed April 13, 1908. Serial No. 426,680.

To all whom it may concern:

Be it known that I, ANDREW W. HARPSTRITE, a citizen of the United States, residing at Moweaqua, in the county of Shelby and State of Illinois, have invented certain new and useful Improvements in Motor-Vehicles, of which the following is a specification, reference being had to the accompanying drawings.

10 My invention relates to improvements in motor-vehicles; and an object of my invention is to provide a motor-vehicle which will be simple in construction, comparatively cheap in manufacture and highly efficient and durable in use.

Another object of my invention is to provide a motor-vehicle particularly adapted for use in agricultural communities, where the exigencies of use demand a varied employment of the motor-vehicle; as, for carrying the soil-turning devices in plowing, the transportation of produce to the market and the carrying from point to point of the farm articles needed for use on the premises.

25 In the drawings illustrating the principle of my invention, Figure 1 is an elevation of my new motor-vehicle; Fig. 2 is a plan view, the engine being shown in dotted lines; Fig. 3 is a detail of the clutch; Fig. 4 is a detail 30 in plan of the axle-adjusting device; and Fig. 5 is a sectional view of the same.

The mechanism for propelling the vehicle comprises an engine *a* of any suitable type (a gas engine is preferred, because of its 35 compact nature, its adaptability to use where units of small power are needed and its small cost of attendance and up-keep) which is mounted upon the frame *b* and upon the main shaft *c* of which is fast a pulley *d* belt-connected to the pulley *e* loose upon the transverse shaft *f*. Upon the latter are also mounted the pinion *g*, the fly-wheel *h* and the slidable clutch *i*, the latter being keyed to the shaft *f*. Parallel with the latter shaft 45 is the shaft *j* upon which are mounted the sprockets *k* and the spur-gear *m*, the latter being in mesh with and hence driven by the pinion *g*. In the rear of the main frame *b* is mounted a propeller shaft *n* which is 50 driven by the sprockets *o* connected by the

drive-chains *p* with the sprockets *k*. Upon the shaft *n* is mounted the traction or propeller wheel *q*.

The clutch *i* is shown in Fig. 3 in detail and is formed with a circumferential groove 55 *r* within which engages the forked lower end of a clutch-lever *s* held in its adjusted position by the engagement of the latch device *t* with the toothed segment *u*.

The driver sits in the seat *v* and steers the vehicle by means of the hand-wheel or steering-wheel *w* mounted upon the rod *x* at the rear end thereof, the front end (Fig. 2) being journaled at *y* in the frame *b* and provided with a grooved collar or hub *z* from 60 which project the pins or studs *2* which engage the links of the steering chain *3*. The ends of the latter are connected to the rear end of the bars *4* by rods *5*. The front end of the bars *4* are connected by the rods *6* the 65 inner ends of which are joined by a turn-buckle *7*. The bars *4* are secured to the brackets *8* which are hinged at *9* (Figs. 4 and 5) to the front part of the main frame *b*, (Fig. 2), and which support the axle *10* upon which turn the front wheels *11*. The latter may be adjusted vertically so as to level the vehicle by turning the crank-handles *12*, each of which is fastened to the top of a screw *13* the lower end of which 70 engages a block *14* from the outer face of which projects one of the axles *10* and which itself is free to slide bodily and carry the axle or spindle *10* up or down, when the crank *12* is turned. The screw *13* is formed 75 near its upper end with a collar *15* and is free to rotate in the top-plate *16*.

This application is filed as a divisional application under my pending application Serial No. 339,368, filed October 17, 1906. 80

I claim:

A motor vehicle consisting of the combination of a frame; propelling devices mounted therein; brackets hinged to said frame; axle-carrying slide-blocks mounted upon said brackets; screws mounted in said brackets and in engagement with said slide-blocks, whereby the latter may be adjusted; a steering rod provided with a grooved hub at its lower end, said hub having studs projecting 85 90 95 100

from it; a steering chain which is wound around said hub and the links of which are adapted to engage said studs; bars mounted upon said brackets, the ends of said chain being connected to said bars; and adjustable means independent of said chain for connecting said bars.

In testimony whereof I have hereunto set

my hand at said Moweaqua in the presence of the two undersigned witnesses this twenty-eighth day of March, 1908. 10

ANDREW W. HARPSTRITE.
